DESIGN FOR A KNITTED FABRIC

Jack Minoff, Brooklyn, N. Y.

Application December 21, 1935, Serial No. 60,215

Term of patent 3½ years

To all whom it may concern:

Be it known that I, Jack Minoff, a citizen of the United States and a resident of the Borough of Brooklyn, city of New York, county of Kings, and State of New York, have invented a new, original, and ornamental Design for a Knitted Fabric, of which the following is a specification, reference being had to the accompanying drawing, forming part thereof.

The figure is a plan view of the knitted fabric, showing my new design.

The design is to be used principally in knitted fabric, made on circular knitting machines. The

holes represent perforations in the fabric made during its manufacture. In addition to the perforations, ornamentations are provided between columns of perforations and also at one portion of the perforations, as shown in the figures of the accompanying drawing, and are formed by open stitch, using threads of a color different from that of the fabric.

I claim:

The ornamental design for a knitted fabric, as shown and described.

JACK MINOFF.
